US00D610171S

(12) **United States Design Patent**
Schmidt

(10) **Patent No.:** US D610,171 S
(45) **Date of Patent:** ** Feb. 16, 2010

(54) **CONSTRUCTION MACHINE**

(75) Inventor: **Hans-Heinrich Schmidt,**
Lichtenfels-Sachsenberg (DE)

(73) Assignee: **Weidemann GmbH**, Diemelsee (DE)

(**) Term: **14 Years**

(21) Appl. No.: **29/315,586**

(22) Filed: **Jul. 7, 2009**

Related U.S. Application Data

(60) Division of application No. 29/313,409, filed on Jan. 2, 2009, which is a continuation-in-part of application No. 29/266,033, filed on Sep. 13, 2006, now abandoned.

(57) **CLAIM**

The ornamental design for construction machine, as shown and described.

DESCRIPTION

FIG. 1 is a side view of a construction machine according to my new design;

FIG. 2 is a side view of the construction machine as shown in FIG. 1, shown from the opposite side as that shown in FIG. 1;

FIG. 3 is a front view of the construction machine as shown in FIG. 1;

FIG. 4 is a rear view of the construction machine as shown in FIG. 1;

FIG. 5 is a top view of the construction machine as shown in FIG. 1; and,

FIG. 6 is a bottom view of the construction machine as shown in FIG. 1.

The broken line showing of the circular and triangular elements in FIGS. 1, 2, and 4 is included for the purpose of illustrating a portion of the construction machine and forms no part of the claimed design.
